[57] CLAIM

The ornamental design for a combined adapter and
dispenser for a bird feeder, as shown and described.

DESCRIPTION

FIG. 1 is a perspective view of a combined adapter and
dispenser for a bird feeder embodying my new design;

FIG. 2 is a top view thereof;

FIG. 3 is a side view thereof, the opposite side is identi-
cal;

FIG. 4 is a bottom view thereof; and,

FIG. 5 is an end view thereof, the opposite end is identi-
cal.

FIG. 1

FIG. 2

FIG. 3

FIG. 4

FIG. 5
